R. MARI.

SAFETY RAZOR.

APPLICATION FILED OCT. 5, 1915.

1,187,357.

Patented June 13, 1916.

UNITED STATES PATENT OFFICE.

RODOLFO MARI, OF ROSARIO DE SANTA FÉ, ARGENTINA.

SAFETY-RAZOR.

1,187,357.

Specification of Letters Patent. Patented June 13, 1916.

Application filed October 5, 1915. Serial No. 54,188.

To all whom it may concern:

Be it known that I, RODOLFO MARI, a subject of the King of Italy, and resident of No. 1132 San Martin street, Rosario de Santa Fé, Republic of Argentina, have invented certain new and useful Improvements in Safety-Razors, of which the following is a specification.

This invention relates to a novel type of safety razor and has for object to provide certain improvements which tend to render its use more practical while cheapening at the same time its construction.

The invention refers more particularly to safety razors which may be used in the same way as ordinary razors, that is to say, safety razors provided with the usual form of handle or shell and therefore adapted to be handled as a common razor. This type of razor offers the advantage that the hand always assumes its usual position and that the cutting edge may accommodate itself much better to the face, so that the operation of shaving requires less time and may be carried out more safely and perfectly.

A further advantage of the safety razor according to this invention is that the same may be mounted and dismounted speedily and without any difficulty, while at the same time, owing to the particular arrangement of its different parts, it is not liable to get dirty as there are no inner or hidden parts to which the soap might gain access. This latter fact constitutes a serious drawback of most of the known safety razors, in connection with which considerable time is lost in cleaning the same during use.

A further object of this invention is to provide means for adjusting the razor, so as to allow the same to readily accommodate itself to more or less strongly developed beards, this purpose being realized in a very simple manner, as will hereinafter be fully explained.

In order that this invention may be readily and clearly understood and carried into practice, a preferred form of construction of the same has been represented in the annexed drawings, wherein:—

Figure 1 is a plan view of a double metallic comb, being one of the several parts which constitute the safety razor in accordance with the present invention. Fig. 1^a is a similar view of the cutting blade provided, as in most of the known safety razors, with two cutting edges, in order to prolong

its use. Fig. 1^b is a similar view of the main or body part of the razor, provided with its corresponding handle, adapted to be partially folded. Fig. 1^c is a view similar to that of Fig. 1^b but at right angles thereto. Fig. 2 is a sectional view of the parts shown in Figs. 1, 1^a and 1^b, in the superposed position occupied thereby when the apparatus is to be used. Fig. 3 is an upper view of the operating part of the safety razor, with the several parts in superposed position ready for being fixed in place. Fig. 4 is a view similar to that of Fig. 3, the razor being ready for use. Fig. 5 is a view, on a larger scale, of the particular device employed for connecting the parts together, and finally Fig. 6 illustrates a longitudinal section through the double comb of Fig. 1.

In all figures of the drawings, similar letters of reference indicate like parts.

The main part or body piece of the safety razor consists of a metallic frame to which is pivoted in any suitable way the handle *t*, of ivory, bone, wood or other convenient material. The said metallic body piece to a certain extent affects the shape of a common razor, being fluted at its lateral edges, as indicated at *r*, and has a central cavity (as clearly shown in Figs. 1^b and 1^c), for the purpose of providing a support for the fingers when the razor is being used. The metallic body is enlarged at its end opposite to the handle *t*, forming the part *c*, conveniently bent as may be clearly seen in Fig. 2, and said part is provided at its concave face with pins or other fastening means *h*, of which a detail view is shown in Fig. 5, on an enlarged scale.

The double comb has been designated in the drawings with the reference letter *a*; the same is also made of metal, being provided with a suitable number of teeth *e* at both sides and with a milled button *d* at its center, so as to be able to handle the same with the fingers and fix it in position without slipping. Said double comb *a* is further provided with two rectangular holes *f* which register with the pins or similar fastening devices *h* of the body part *c* of the razor and serve to fix the whole of the apparatus in position, in the manner hereinafter pointed out. The fastening devices each have a reduced neck portion, one edge of which is curved upwardly as at *h*⁴ to form a wedge and at the upper end is an overhanging projection *h*⁵.

As will be seen on inspecting the section view shown in Fig. 6, there is a difference of level between one side and the other of each of the rectangular openings *f*, so that while on one of the sides the opening is at *m* at the same level as the remainder of the comb, at the opposite there is formed a recess *p*, shaped like a nail or of other suitable form, the level of which is somewhat lower than that of *m*. The purpose of this difference of level will be explained later on. The double comb *a* is also bent or curved like the body part *c* of the razor, as will be seen in Fig. 2, and the button *d* is placed at its center, on the concave face of the same.

b is the cutting blade of the razor which, as previously stated, has two cutting edges and is provided with the holes *g* which also register with the buttons or studs *h*, and fit thereon, while allowing of a certain amount of movement of the blade on said studs.

To assemble the parts in position, after all of the different parts being thoroughly cleaned, I proceed as follows: The cutting blade *b* is placed into the concave part of the body piece or frame *c* of the razor, care being taken to cause the orifices *g* to register with the studs or pins *h*. Now, onto said blade *b* is placed the double comb *a*, with the rectangular openings *f* of the same also registering with the aforementioned studs *h*, as clearly shown in Fig. 3 of the accompanying drawings. In this figure, the edge *m* of the openings is directed toward the lower part, while the edge *p* of the same is directed upward.

The convexity of the parts *a* and *c* differs, the former being considerably flatter, so that both parts, after being simply superposed, will not come into contact with each other, this fact being besides prevented by the resistance opposed by the cutting blade *b*. In order to firmly secure all the parts together, a slight pressure must be exerted on the button *d*, placed at the middle of the convex part of the comb *a*, so as to cause the comb to flex owing to its proper resiliency; the comb will draw with it the cutting blade *b* the edges of which will fit inside of the part *c* of the body part of the razor and its openings *f* will pass below the incisions or cuts formed on the studs *h*; in order to realize this purpose, it will be sufficient, while submitting the button *d* to pressure, to impart thereto a slight movement in direction toward the handle *t* of the safety razor. This latter will finally assume the position illustrated at Fig. 4, being now ready for use.

In the case shown here, the notch or recess of the studs *h* bears on the part *m* of the openings *f*, that is to say, on the part of higher level, so that the pressure exerted by the double comb *a* on the cutting blade *b*

is stronger than if the said notches bore on the recessed part *p* of the said openings *f*, and the cutting edge of the blade *b* will therefore lay itself snugly on the teeth *e* of the double comb *a*.

When the comb *a* is placed over the fastening devices it is forced toward the right, viewing Fig. 1^c, and the walls of the slots adjacent the depressions are opposite the upwardly curved edges of the necks. When the comb is moved toward the right the walls of the slots adjacent the depressions engage with the curved portions of the necks of the fastening devices, the latter acting as wedges to cause the overhanging portions of the fastening devices to tightly engage the bottom walls of the depressions. In order to vary this pressure, the double comb *a* is turned on its proper plane so that the part which formerly was up (Figs. 3 and 4), will now be placed down; as for the remainder, the operation of adjusting the parts is the same as before, taking care that when sliding the double comb *a*, the recessed parts *p* which form one of the edges of its two openings *f*, shall remain keyed to the fastening stud *h*.

As the different parts which constitute the safety razor, are in snug contact with each other and there are no internal pieces, there is no liability for the soap to get into the interior of the razor when being operated, so that shaving may be effected much more speedily and with less trouble than with the safety razors as known heretofore.

For dismounting the razor, the proceeding is reversed. Pressure is exerted on the bottom *d* of the metallic comb *a*, while at the same time a slight sliding movement is imparted thereto in a direction opposed to the handle *t* of the razor whereby the openings *f* will be released from the studs *h*, at *p* or at *m*, as the case may be, and the comb, owing to its proper resiliency, will recover its original position, of less convexity than the piece *c* of the razor, or that which is shown in Fig. 3 of the annexed drawings. The several parts may then be separated without any difficulty, and suitably cleaned in order to be ready for the next use.

It will be evident that the construction of this safety razor may be modified and changes may as well be introduced as regards the relative dimensions of the parts forming the same and their degree of curvature, without departing from the essential object of this invention of which the main features will be clearly pointed out in the final claim.

Having now particularly described and ascertained the nature of my said invention and the manner in which the same is to be performed, I declare that what I claim is:

In a razor, the combination with a body piece, of a plurality of pins projecting there-

from, each of said pins being provided with an upwardly curving cut out portion and a laterally projecting circular head above the cut out portion, a blade provided with openings corresponding to the pins, a comb member provided with openings corresponding to the pins, the face of the comb member being provided with a depression adjacent each opening to engage the heads of the pins projecting therethrough, whereby lateral movement of the comb member will cause the heads on the pins to engage or disengage said depressions, and the end walls of the slots in the comb will engage the upwardly curved cut portions of the fastening

devices and act as a wedge and thereby force the bottom walls of the depressions against the underside of the lateral projections when assembling the parts, the comb member having a serrated projection on the outer side thereof by means of which the member may be moved in the proper direction. 20

Signed at Rosario de Santa Fé, Argentina, this 27th day of August A. D. 1915.

RODOLFO MARI.
